Primary Examiner — Rhea Shields(74) Attorney, Agent, or Firm — Amster, Rothstein & Ebenstein LLP(57) CLAIM

The ornamental design for a cosmetic product hang tag, as shown and described.

DESCRIPTION

FIG. 1 is a top plan view of an embodiment of a new design for a cosmetic product hang tag;

FIG. 2 is a side view, thereof;

FIG. 3 is a front view, thereof; and,

FIG. 4 is a rear view.

The cosmetic product hang tag is shown with a symbolic break in its length. The appearance of any portion of the article between the break lines forms no part of the claimed design. In the drawings, the broken lines are for the purpose of illustrating portions of the cosmetic product hang tag that form no part of the claimed design.
